UNITED STATES PATENT OFFICE.

HAROLD E. FOX, OF PITTSBURGH, PENNSYLVANIA, ASSIGNOR TO CENTRAL ELECTRIC TOOL COMPANY, A CORPORATION OF PENNSYLVANIA.

ELECTRICAL CONTROL SYSTEM.

Application filed January 20, 1925. Serial No. 3,696.

This invention relates to electrical control systems and is particularly adaptable to systems for controlling sign flashing and for controlling the operation of hoist or elevator motors, or circuits, or devices to be periodically energized.

The object of this invention is to provide a novel method of and means for opening an alternating current circuit without drawing an arc.

Another object of my invention is to provide a control system which shall be relatively simple, reliable and economical.

In practicing my invention, I provide two unilateral current conducting devices, preferably electronic tubes, and two relays, one in series with each tube, between the alternating current supply circuit and the load circuit. The two circuits, each including an electronic valve and a relay, are connected in inverted parallel relation, that is, one tube is connected in such manner as to transmit the positive current impulses and the other tube to transmit the negative current impulses. Each of the circuits includes a switching element of the relay, which is held closed while the relay is energized but which opens when the current traversing the tube and the relay decreases to zero, unless the relay switch is otherwise held closed. Each relay is provided with an operating winding which may be periodically energized as by a motor driven switch for flashing, or by an elevator operating switch, or other equivalent means. When the operating windings are so energized, the relays connect the electronic valve between the supply circuit and the load circuit to transmit current therebetween. When it is desired to disconnect the load circuit and the switch is opened, the operating coils of the relays are de-energized but the holding coils which are in series with the electronic valves remain energized until the current through the associated valve decreases to zero. The relay switches thereupon open to disconnect the associated valves from the load circuit.

Since each valve is so connected as to transmit impulses of only one polarity, no current will traverse the respective valves for the duration of the intervals between such impulses. Inasmuch as one valve is connected to transmit the positive current impulses and the other to transmit negative current impulses, the sine wave alternating

current will be transmitted to the load circuit so long as both relay switches are closed. As soon as the operating switch that operates the relays is opened, the only current that can hold the relay switch in closed position is that traversing the respective associated valves. Since the current through each valve decreases to zero, the associated relay switch will open. The two switches should open within practically one cycle after the main operating switch has been opened. Inasmuch as the relay switches open when there is no current traversing the electron valves and, consequently, the relay switches, there will be no arcing when the load circuit is disconnected from the supply circuit.

In Fig. 1 of the accompanying drawings, is a diagrammatic view of an electrical circuit containing apparatus arranged to operate in accordance with the foregoing description;

Fig. 2 is a schematic view of the system illustrated in Fig. 1, illustrating a motor-operated switch for sign flashing or similar work;

Fig. 3 is a diagrammatic view of an elevator motor system operating in accordance with the principle of the system illustrated in Fig. 1; and

Fig. 4 is a graphic view of the current wave impulses transmitted by the respective electric valves.

As illustrated in Figs. 1 and 2, alternating current energy is derived from a generator or alternating current supply circuit 1 and supplied to a load circuit 2 containing electric lamps 3 or inductive load 4. Two electric valves 5 and 6 of the electronic type and two relays 7 and 8 are provided to connect the load circuit 2 and the connected load to the supply circuit 1, when such connection is desired, in response to the closure of the switch 9, which may be manually operated as in Fig. 1, or switch 25 motor operated as illustrated in Fig. 2.

The valves 5 and 6 in the example illustrated are of the electronic type, comprising an electron-emitting filament *f* and an anode or plate *a* in a closed vessel. Energy for the filaments of both valves is derived from the circuit 1 through a transformer 11, the primary winding of which is controlled by a relay switch 12 in response to the operation of the main switch 9. The relay 7 embodies

a switch element 13, an operating coil 14 and a holding coil 15. Similarly, the relay 8 embodies a switch 16, an operating coil 17 and a holding coil 18.

- 5 The filament of the valve 5 and the plate of the valve 6 are connected to conductor 20 of the supply circuit 1. The plate of valve 5 is connected in circuit with the holding coil 15 and the switch element 13 of the relay 7. Similarly, the filament of the valve 6 is connected in circuit with the holding coil 18 and the switch element 16 of relay 8. The switch elements 13 and 16 of the relay 7 and 8 are joined and connected to the 15 load circuit 2 by a conductor 21. The operating coils 14 and 17 of the two relays 7 and 8 are connected in series with the winding of relay 12 and the main switch 9 across the supply circuit 1. Thus, when the switch 20 9 is closed, the relay 12 closes to energize the filaments of the electronic valves 5 and 6, and to operate the relays 7 and 8 to close the associated switches 13 and 16. The circuit 2 is then connected to the circuit 1 25 through the switches 7 and 8 and the valves 5 and 6.

When the conductor 20 is negative with respect to the other conductor 22 of the supply circuit 1, the filament of valve 5 is negative with respect to its plate, and current 30 will therefore be transmitted by the valve 5 from the supply circuit 1 to the load circuit 2. At the same time, however, the plate of valve 6 will be negative with respect to 35 its filament, and the valve 6 will therefore be non-conductive and will not transmit current between the supply and load circuits. As the polarity of the circuit changes, however, and the conductor 20 becomes positive, the valve 5 becomes non-conductive since its filament is now positive with respect to its plate. At the same time, 40 however, the valve 6 becomes conductive since the plate is positive with respect to the 45 filament which is the condition conductive to current conduction.

Thus, upon closure of the switch 9, the 50 filaments of the valves are energized and the relays 7 and 8 are operated to connect the valves 5 and 6 between the supply and load circuits, and current is transmitted therebetween. As soon as the switch 9 is 55 opened, the operating coils 14 and 17 are de-energized. So long as current traverses the windings 15 and 18, however, their 60 switches will remain closed. Inasmuch as the valve 5 will transmit only impulses of one polarity and the valve 6 only impulses of opposite polarity, there will be intervals between such impulses when no current will be 65 transmitted, as illustrated in Fig. 4, in which V is the electromotive-force and 5 and 6 are the current impulses through the valves 5 and 6. Consequently, the associated holding windings 15 and 18 will be de-ener-

gized during such intervals and the relays 7 and 8 will assume their normal de-energized positions. The valves 5 and 6 will thus be disconnected from the load circuit and no current will be transmitted to the 70 load circuit from the supply circuit 1.

Inasmuch as the relay switches 13 and 16 open when no current is traversing the circuit in which they are disposed, there is no 75 arcing to attend such opening and, consequently, there is nothing to cause deterioration of the switch contacts.

In Fig. 1, I have illustrated the switch 9 as being a manually operable switch. In Fig. 2, I have illustrated a motor-operated 80 switch in which the switching operations are controlled by a contact on a drum 25 which is controlled by a motor 26 that is energized from the supply circuit 1. The timing device 27 is shown schematically. It 85 may be of any of the well known commercial time switches which close at a predetermined time and remain closed for a definite interval, as, for example, during the 90 evening hours when the operation of the sign flashing device may be desired.

In Fig. 3, I have illustrated a circuit for controlling the operation of a hoist or elevator motor. Energy is derived from a polyphase alternating current generator or 95 supply circuit 30 and is supplied to a hoist or elevator motor 31 through a starting and reversing apparatus 32 and non-arcing units 35, 36 and 37, each of which is disposed in a conductor between the generator or supply circuit and the motor. The starting and reversing apparatus is illustrated for simplicity merely by a rectangle since the operation and construction of such apparatus is well known and need not be described in 100 detail other than to specify the function thereof.

The several non-arcing units 35, 36 and 110 37 are similar to the units illustrated and described in Figs. 1 and 2. The operation of the starting and reversing apparatus 32 and the connection of the non-arcing units 115 thereby, between the generator and the motor, are controlled by a switch 38 which is disposed on the elevator and is subject to control of the operator. The switch 38 comprises a movable member 39 which engages contacts 40 and 41 when moved to the left hand side, and contacts 42 and 43 when moved to the right hand side. The 120 switch 38 is adapted when operated in one direction to complete a circuit including all of the operating coils of the relays associated with the valves of the non-arcing units, thereby closing the switches and connecting 125 the circuits of the valves between the generator and the motor. At the same time a circuit is completed that controls the operation of the starting and reversing switching apparatus which connects the generator 130

by gradual voltage or current steps to the motor, to permit the motor to accelerate in response to gradually increased energization. When operation of the motor is no longer desired, the switch 39 is opened, and the non-arcing units respectively open the associated relay switches to disconnect the associated conductors until the motor is disconnected from the generator.

10 When operation of the motor is desired in a reversed direction, the switch 39 is operated to the opposite side. The non-arcing units are again connected in circuit between the generator and motor, and the 15 starting and the reversing apparatus 32 is properly operated to connect the motor to the generator to cause the motor to rotate in a reversed direction. When the operation of the motor is again no longer desired, 20 the main switch is opened by the operator and the non-arcing units again operate to open their respective circuits when no current traverses the valves.

By means of a system of the foregoing 25 character in which the circuits are opened when no current traverses the circuit for an interval of extended duration, all arcing is obviated and excessive wear due to burning and pitting of contact surfaces is eliminated.

30 My invention is not limited to the specific devices that are illustrated, nor to the arrangement that is shown, but may be modified without departing from the spirit and scope of the invention as set forth in the 35 appended claims.

I claim as my invention:

1. The combination with a source of alternating current, of an electric valve and a switch in series with each other in the circuit of said source for transmitting the load current thereof, means energized by the load current transmitted through said valve and switch for holding said switch closed until the current through said valve falls to substantially zero magnitude and means thereupon effecting opening of said switch.

2. The combination with a source of alternating current, of an electric valve and a switch biased toward open position in series with each other in the circuit of said source for transmitting the load current thereof, means energized by the load current transmitted through said valve and switch for holding said switch closed until the current through said valve falls to substantially zero magnitude and means thereupon effecting opening of said switch.

3. The combination with a source of alternating current, of an electric valve and a switch in series with each other in the circuit of said source for transmitting the load current thereof, an operating coil for moving said switch to closed position, a holding coil traversed by load current transmitted through said valve for holding said switch

in closed position after deenergization of said operating coil until the current through said valve falls to substantially zero magnitude and means thereupon effecting opening of said switch.

4. The combination with a source of alternating current, of an electric valve continuously asymmetrically conductive, a switch in series with said valve in the circuit of said source and through which and said valve the load current of said source is transmitted, and means responsive to the fall of current in said valve to substantially zero magnitude causing said switch to open.

5. The combination with a source of alternating current, of an electric valve and a switch in series with each other in the circuit of said source for transmitting the load current thereof, an operating coil for moving and holding said switch to and in closed position, a holding coil energized by the load current traversing said valve for holding the switch closed after deenergization of the operating coil until the current through said valve falls substantially to zero magnitude and means thereupon effecting opening of said switch.

6. The combination with a source of alternating current, of an electric valve and a switch in series with each other in the circuit of said source for transmitting the load current thereof, an operating coil for moving said switch to closed position, a holding coil traversed by load current transmitted through said valve for holding said switch in closed position after deenergization of said operating coil until the current through said valve falls to substantially zero magnitude, means for maintaining said valve conductive, and switching mechanism for controlling simultaneous energization of said means and of said operating coil.

7. The combination with a source of alternating current, of a thermionic valve and a switch in series with each other in the circuit of said source and through which the load current of said source is transmitted, means controlled by the current transmitted through said valve for holding said switch closed until the current through said valve falls substantially to zero magnitude and means thereupon effecting opening of said switch.

8. The combination with a source of alternating current, of a thermionic valve and a switch in series with each other in the circuit of said source and through which the load current of said source is transmitted, means controlled by the current transmitted through said valve for holding said switch closed until the current through said valve falls substantially to zero magnitude and means thereupon effecting opening of said switch, an operating coil for moving said switch to closed position, and switching

mechanism controlling the simultaneous energization of the cathode of said valve and of said operating coil.

9. The combination with a source of alternating current, of a pair of electric valves connected in inverted parallel relation with each other, a switch in series with each of said valves, said valves and switches transmitting the load current of said source, normally energized electro-magnetic means holding said switches closed while said load

current is flowing, electro-magnetic means controlled by the valve current for holding said switches closed after deenergization of said first named electro-magnetic means ¹⁵ until the valve current falls substantially to zero magnitude and means thereupon effecting opening of said switch.

In testimony whereof, I have hereunto subscribed my name this 19th day of January, 1925.

HAROLD E. FOX.
